MACHINE TOOL

Konrad Rauch, Dayton, Ohio, assignor to The Sheffield Corporation, Dayton, Ohio, a corporation of Ohio

Application June 21, 1943, Serial No. 491,577

23 Claims. (Cl. 125—11)

This invention relates to grinding apparatus and more particularly to trimming or truing devices for grinding wheels.

One object of the invention is the provision, in a grinding apparatus, of wheel truing mechanism, including a pair of wheel trimmers, arranged for movement at a desired angular relationship, and automatically operated by simple means including angularly movable arms and slide devices providing for a combination of different rectilinear motions which produce the desired resulting movements of the wheel trimmers.

Another object of the invention is the provision of wheel trimming mechanism arranged in a carrier which is supported in a grinding wheel support, the grinding wheel support being arranged for adjustment about an axis perpendicular to the grinding wheel axis in accordance with the helix angle of a thread to be ground, and the carrier having a plurality of portions one of which is arranged for both axial and rotational movement in the grinding wheel support and the other of which is adjustably connected to the first portion and has axial movement only.

Another object is the provision of wheel trimming mechanism including a carrier having a portion which is axially movable in a passage in the grinding wheel support, the carrier having an adjustable connection with an abutment portion that is detachably carried by the foot portion of a fixed standard, and so arranged that the abutment portion can be removed as a unit with the carrier without disturbing operating connections between that abutment portion and other portions of the carrier.

Another object is the provision of a wheel trimming device including a carrier which is rotatably and axially movable in a passage in a grinding wheel support and so arranged that both the carrier and the grinding wheel support are independently adjustable about an axis perpendicular to the grinding wheel axis, the carrier including an end portion that is carried for rolling movement on a standard fixed on the frame that carries the grinding wheel support.

Another object is the provision of a wheel trimming device having a pair of relatively movable wheel trimmer holders and mechanism for automatically operating said holders to advance the holders towards the grinding wheel and for moving the holders in opposite directions to produce the desired angles on the faces of the grinding wheel, each holder carrying a diamond mount which is readily separable from the holder in a

direction substantially tangential of the grinding wheel, without removing the holder operating mechanism or the grinding wheel.

Other objects and advantages of the invention will be apparent from the following description, the appended claims, and the accompanying drawings, in which:

Fig. 1 is a top plan view of a portion of a grinding machine embodying the present invention;

Fig. 2 is a vertical section on the line 2—2 of Fig. 1;

Fig. 3 is a horizontal section on the line 3—3 of Fig. 2;

Fig. 4 is an end view of the diamond holders looking in the direction of the arrow 4 shown in Fig. 3;

Fig. 5 is an end view of the wheel trimming apparatus looking in the direction of the arrow 5 in Fig. 2;

Fig. 6 is a vertical section on the line 6—6 of Fig. 2;

Fig. 7 is a section on the line 7—7 of Fig. 3;

Fig. 8 is a section on the line 8—8 of Fig. 3;

Fig. 9 is a diagrammatic showing of the toggle mechanism for operating the trimmer holders; and

Fig. 10 is a diagrammatic showing of the motions imparted to the trimmers.

Referring more particularly to the drawings, in which a preferred embodiment of the invention has been illustrated in association with a thread grinding machine, 10 generally designates the main machine base having suitable work supporting and turning devices and suitable means of any desired character for traversing the work axially with respect to a rotatable grinding wheel 11 so that the grinding wheel will grind a thread of the desired pitch and angle on the workpiece.

The grinding wheel 11 is rotatably mounted in a grinding wheel support 12 having an arbor supporting portion in which the grinding wheel arbor is rotatably carried, this arbor supporting portion projecting from a body portion 13. This body portion 13 constitutes a barrel-like member which is rotatably adjustable in a stationary bearing ring forming part of the wheel slide frame 14 which is mounted for rectilinear movement on the main base to move the wheel towards and from the work. The rotatable mounting of the barrel 13 permits the whole grinding wheel support to be rotatably adjusted about an axis extending perpendicularly to the grinding wheel axis and perpendicularly to the work axis so that

the grinding wheel can be presented to the work while rotating in a plane which is properly inclined to the work axis, in accordance with the helix angle of the thread to be produced. Adjustment of the barrel 13 is effected by rotating a hand wheel 15 which operates a worm 16 engaging the teeth of a worm wheel 17 provided on the barrel 13, worm 16 being arranged on a worm shaft 18 which is rotatably carried in brackets provided on the frame 14. Any position of adjustment of the barrel 13 is securely maintained by tightening bolts 19 which secure end plate 20 tightly against the frame 14 which is fixed against rotation.

The barrel 13 is provided with a passage 22 extending perpendicularly of the work axis and of the grinding wheel axis, passage 22 having a finished cylindrical slide surface 23 of considerable diameter, slidably supporting a carrier 24. The carrier 24 forms the support or carrying means for wheel truing mechanism and the motor for operating that mechanism, so that the wheel truing devices, which are preferably truing diamonds, are automatically moved at the proper angle of divergence along adjacent surfaces of the grinding wheel. The truing diamonds, shown at 25 and 26, are arranged in holders 27 and 28 respectively. The motor which operates these holders is shown at 29, and the operating mechanism arranged between the motor and the holders is arranged in the carrier 24, these parts all constituting a unit which is readily operable in and removable from the grinding wheel support at a location which is diametrically opposite the zone of grinding contact with the work.

The carrier 24 comprises a housing portion which is of generally cylindrical form, one end of the housing portion being closed by an end wall 31. Bolts 32 secure the end wall to the housing portion, these bolts threading into the housing portion and extending through arcuate slots 33 in the end wall so that the end wall, which does not have a rotatable adjustment, can permit relative rotation of the housing portion in order to compensate as required for any inaccuracies produced by the inclination of the grinding wheel in accordance with the helix angle of the thread to be ground.

The entire carrier including the end wall 31 is bodily movable towards the grinding wheel axis, and the housing portion of the carrier also has the rotatable adjustment just mentioned, both movements of the housing portion causing relative sliding movement of its forward end on the grinding wheel support 12. The wheel trimmer holders 27 and 28 move bodily in the carrier in a common plane and in diverging directions on a pair of parallel guide bars 35, 35' which are themselves movable in the carrier towards and from the grinding wheel as will be more fully described. Thus the trimmers or diamonds, when the bars 35, 35' are horizontal, move in a horizontal plane through the axis of the grinding wheel and trim the grinding wheel diametrically opposite the zone where the grinding takes place on the work. By rotatably adjusting the housing portion of the carrier, this plane in which the diamonds move can be inclined to compensate for any required thread form. As will be apparent, the plane in which the diamonds move can be horizontal or substantially horizontal even though the grinding wheel itself is inclined in accordance with the helix angle of the thread to be ground.

The rear end of the carrier is supported by

spherical or cylindrical rollers for rolling movement on a standard 37 which is fixed to or forms a part of the frame 14. Standard 37 is of generally U shape, having a foot portion 38 and upwardly extending legs 39, the upper side of the standard thus having a deep recess 40 past which the entire carrier can be moved. The legs 39 carry tracks 41 the upper surfaces of which are parallel to the axis of the carrier, these tracks being arranged outwardly of the confines of the passage 22. The end wall 31 of the carrier reaches out laterally as shown in Fig. 5 and is provided with rollers 42 operating along the tracks 41. The rear end of the carrier is thus mounted for rolling movement at points widely spaced from the axis of the carrier, preventing any rotational movement of the end wall of the carrier. Since the end wall of the carrier is held securely to the housing portion of the carrier the latter is movable along the passage in the grinding wheel support, without rotating.

The standard 37, near the upper ends of its leg portions, is provided with an abutment portion or bar 43 which normally extends across the end of the carrier and which is normally secured firmly to the legs of the standard by means of threaded screws 44 pivoted at 45 to the legs of the standard and extending through slots 46 in the abutment bar. Wing nuts 47 are tightened on the screws against the abutment bar, and by loosening these nuts the screws 44 may be swung on their pivot axes to entirely disconnect the abutment bar from the foot portion of the standard.

The abutment bar rotatably carries a threaded shaft 49 which is held against endwise movement and against rotation by a clamp plate 50 screwed to the abutment bar and clamping against a shoulder on the shaft 49 as shown in Fig. 4. Screw threads 51 on the shaft 49 extend through a rotatable nut 52 which is held against endwise movement in the end wall 31. The nut 52 is secured to a ratchet wheel 53 which is stepped along by a ratchet pawl 54 controlled by solenoid 55. The solenoid is energized at the start of a truing cycle in order to move the ratchet pawl 54 and thus turn the nut 52 a portion of a revolution so as to increase the distance between the end wall 31 and the abutment bar, causing a feeding movement of the entire carrier. The amount of this feeding movement corresponds to the desired amount of removal of the material in a truing cycle.

As the wheel is reduced in size, the space between the end wall and the abutment bar increases. When it becomes necessary to replace the grinding wheel with a new one of larger diameter, the carrier is moved back to its initial position with respect to the abutment bar by loosening the clamp screws which hold plate 50 in place and then turning the square end 56 of shaft 49 to rotate the shaft in the proper direction, the ratchet pawl 54 and a supplementary holding ratchet pawl 57 serving to hold the nut 52 against turning with the shaft 49 in this readjustment of the carrier.

The end wall of the carrier and the abutment bar are interconnected in a yielding manner so that the carrier is constantly urged towards the grinding wheel under a desired spring pressure, resulting in the elimination of lost motion. The springs shown at 58, which are interposed between the end wall and the abutment bar, are arranged in telescoping casing tubes 59 and 60 which are secured respectively to the abutment

bar and to the end wall as shown in Fig. 3. The springs are held under compression, exerting a pushing force on the carrier, the movement of the carrier, however, being controlled in a step by step manner by the timed operation of the nut 52. It should be noted that when the screws 44 which hold the abutment bar in place are loosened and swung outwardly, the abutment bar can move with the carrier without disturbing the relative setting of the abutment bar and the carrier and without disturbing or relieving the spring tension exerted by the springs 58.

The motor 29 is arranged in a compartment provided between the end wall 31 and a web or wall portion 60 of the carrier, and drives a gear train through a speed reduction gear box 61. The gear train comprises gears 62, 63, 64, 65, 66 and 67, the latter being secured to a toothed clutch wheel 68 forming the driving element of a one revolution clutch including a driven plate 69 which is fixed to a shaft 70 journaled in bracket 71 on the carrier. The plate 69 carries a drive arm 72 pivotally supported on the drive plate at 73. The drive arm has a projection 74 engageable with the teeth of wheel 68 and normally held in engagement with those teeth by a spring 75 pinned to the driven plate 69. On the drive arm 72 is a finger 76 which comes up against a stop 77, after one revolution of the driven plate 69 and pulls the arm 72 out of engagement with the toothed wheel. The stop 77 is operated by a solenoid promptly after a truing cycle is initiated so that the stop is pulled out of the path of the projection 76, thus freeing the arm 72 so that it can move into engagement with the rotating clutch wheel 68 and produce one revolution of shaft 70.

Pinned to the shaft 70 is a double plate cam 79 engaging rollers 80 arranged on a slide plate 81. The slide plate 81 is provided with slots 82 and is guided for horizontal movement on a stud 83 and on the shaft 70, the double plate cam serving to positively control the reciprocatory movement of this plate 81. Plate 81 has a slot 85 engaged by and operating the end of a lever 86 which is pivotally supported on a shaft 87. Lever 86 has an arm 88 which is pivotally connected at 89 to a bell crank lever having arms 90 and 91 pivotally supported at 92 on a pin which is arranged in a mount 94. The forward wall of the mount 94 is connected by a flexible bellows 93 to the carrier 24 as shown in Figs. 2 and 3, and is provided with an opening admitting the forwardly extending portions of the holders 27 and 28 and permitting adequate lateral movement of these holders. The bellows 93 serves to retain the lubricant that may be supplied to the operating parts inside the carrier. This mount 94 has bearing rods 95 and 95', see Figs. 2, 3 and 6, extending parallel to the axis of the carrier and slidably carried in guide holes provided in the flanged portions 96 at the forward end of the carrier and in webs 96' on the carrier. Springs 48 arranged on rods 95 between the flanges 96 and the mount 94 yieldingly urge the mount to a retracted position. The mount 94 is thus bodily movable in a direction towards and from the grinding wheel, forward movements taking place from the position shown in Fig. 3 as the plate 81 is moved downwardly as viewed in that figure, thus causing counter-clockwise rotation of lever arms 86 and 88 through an angular travel of 30 degrees as shown. In the retracted position of the mount 94, the arms 88 and 90 both bear a 30 degree relationship to a line through the pin

92 and the shaft 87, and constitute a toggle connection, the arms 88 and 90 moving into aligned positions to advance the mount towards the grinding wheel. This advancing movement of the mount produces the forward component of motion required of the diamonds. The horizontal component of motion of the diamonds is obtained by sliding the diamond holders away from one another on the mount at the same time the mount is moved towards the grinding wheel, the movement of the mount also producing this separating movement of the diamond holders through a toggle connection. For this purpose the arm 91 is pivotally connected by pivot pin 95 to a link 97 which is pivotally connected at 98 to the holder 28 on which the diamond 25 is carried. This holder 28 is slidably supported at its forward end at spaced portions on carrying bar 35 and at its rear end on a rear bar 99 which is fixed in the mount 94. The holder thus moves with the mount in a direction towards and from the grinding wheel. As the mount 94 moves towards the grinding wheel, the pin 92 and the pivot pin 98 both advance, but as they do so, the arm 91 will be swung through 30 degrees to straighten the arm 91 into alignment with the link 97, giving a toggle effect in moving the diamond mount laterally so that the lateral component of motion is in proper proportion to the advancing component of the mount to give the desired 30 degree angle of travel to the diamond as required for truing a grinding wheel designed to cut 60 degree threads on the workpiece.

The other diamond holder 27 is slidably carried on the lower bar 35 with the rear portion of the holder 27 slidable on the rear bar 99. On this holder 27 is a pin 98' which is connected by a toggle linkage 91', 97', see Fig. 9, similar to the links 91 and 97, to the arm 90 so that movements of the toggle link 91' in a clockwise direction through 30 degrees will straighten the toggle connection between the pins 92 and 98' and move the holder 27 in a manner similar but opposite to that of the holder 28. The motions imparted to the mount in the carrier thus have the effect of moving the diamonds as indicated in Figs. 9 and 10, the double plate cam which operates plate 81 being so arranged that after the start of a cycle of rotation of plate 69 of the one revolution clutch, the diamond 25 will move from the point *c* to the point *d* while the diamond 26 moves from the point *c'* to the point *m*. During grinding of the work, however, the diamonds are both retracted back from the grinding wheel, and at the start of a truing cycle they are advanced into the position *c*, *c'* partially by the feeding movement of the whole carrier produced by operation of the solenoid operated ratchet pawl 54 which moves the diamonds from points *a*, *a'* to points *b*, *b'* as shown in Fig. 10, and partly by a motion imparted to the mount 94 to advance the diamonds from points *b*, *b'* to points *c*, *c'*. This motion *b* to *c* is produced, as herein shown, by moving the pivotal support of the lever 86-88 towards the grinding wheel by an eccentric motion of a portion of the shaft 87. This eccentric motion takes place before the arm 86 is moved by plate 81. The shaft 87 has a slotted arm 100 which is controlled by a bell-crank lever 101 pivoted at 102 and having a pin 103 which operates in the slot in arm 100. The slot is so formed that as the bell-crank lever moves clockwise the arm 100 is turned counter-clockwise to advance the pivotal support of the lever 86-88 towards the grinding wheel without producing any substantial rotation

of the lever. The second arm 104 of the bell-crank lever 101 is operated by a cam 105 pinned to shaft 70 and so timed as to cause the eccentric adjustment of the shaft 87 promptly after initiating one revolution of the shaft 70 and before the plate 81 is operated by its double plate cam to swing the arm 86. The diamonds are thus advanced from *b*, *b'* to *c*, *c'*, see Fig. 10, and then turning movement of the arm 86 brings the toggle connections into effect to cause the diamonds to travel in diverging directions at the proper angle. This moves the diamond 25 from *c* to *d*. The cam 105 then permits counter-clockwise return movement of the bell-crank lever 101 to again turn the eccentric shaft 87 back to its initial position, thus causing the diamond 25 to move from the point *d* to point *e* so as to be clear of the grinding wheel. The double plate cam which controls plate 81 then moves back to its initial position, operating the toggle connections between the shaft 87 and the mount and the toggle connections between the mount and the diamond holders so that the diamond 25 moves from point *e* to point *b*. The one revolution clutch then completes its cycle without further movement of the diamonds taking place. At the start of the next cycle, by closing the solenoid 55, a second feed movement takes place to move the carrier bodily so that the diamond is advanced from *b* to *f*. When the solenoid 55 is energized to cause the feeding movement of the carrier, the same circuit completes a circuit which starts the motor 29 and completes a circuit through the solenoid which operates to retract the stopping pin 77 of the one revolution clutch. The operation of the motor 29 thus advances the diamonds from *f* to *h*, the distance between *c* and *h* representing the amount that is removed from the grinding wheel in the preceding truing operation. The advance or feeding movement of the carrier has been exaggerated in Fig. 10 since only a few ten-thousandths of an inch movement is actually required for this purpose in each truing cycle.

Each diamond is arranged as shown in Fig. 4 in a diamond setting 107 having a hole 108 in which a locating dowel 109 on the holder 27 or 28 projects. The setting for the diamond 25, for example, has a boss 110 which extends into a passage in the diamond holder 27, the boss 110 being internally threaded so that the diamond setting can be held securely by tightening the screw 111 having a hexagonal or slotted end so that it can be turned by rotating a tool extending approximately tangentially of the grinding wheel. The two screws 111 for holding the two diamond settings extend parallel to one another, one being arranged to be accessible from above the one from below the holders 27 and 28, so that the diamond settings can be readily removed in a direction perpendicular to a horizontal plane through the grinding wheel axis, or in other words, substantially tangentially with respect to the grinding wheel periphery. This permits removal of the diamond settings from the carrier itself, since the removing tools by which the diamond settings can be loosened can be applied without extending from the grinding wheel axis or through the plane of the grinding wheel. However, if it becomes necessary to repair, replace or inspect any of the parts contained in the carrier, the entire carrier can be readily removed from the grinding wheel support, and this is effected, as already mentioned, without disturbing the setting between the abutment bar and the 75

carrier, and without requiring any adjustment in or loss of tension of the springs 58, since the abutment bar comes off with the carrier as a unit.

In effecting a desired inclination of the grinding wheel itself, by turning the grinding wheel support 12 on its axis in order to accommodate a desired helix angle, no change need be made in the plane in which the truing diamonds operate, and this plane may be maintained horizontal. This is desirable especially where the helix angle is not large, but where some compensation is required, especially in the case of large helix angles, the housing portion of the carrier can easily be rotatably adjusted with respect to the end wall 31. The construction is such, as already mentioned, as to provide for rolling support of one end of the carrier so that it is freely operable towards and from the grinding wheel in effecting adjustments of the carrier and also facilitating the removal of the carrier from the grinding wheel support. The wide spacing of the tracks 40 give a firm support to the carrier at opposite sides of the carrier quite remote from the carrier axis.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a grinding apparatus, in combination, a frame, a grinding wheel support on said frame having a passage extending transversely of the grinding wheel axis, a carrier in said passage having a portion adapted for axial and rotational movement in said passage and a second portion adjustably connected to the first portion and arranged for axial movement only, a standard on said frame, anti-friction means supporting said second portion on said standard for movement thereon, adjusting means for moving the carrier with respect to the standard, wheel truing mechanism in said carrier, and driving means for said mechanism.

2. In a grinding apparatus, in combination, a frame, a grinding wheel support on said frame having a passage extending transversely of the grinding wheel axis, a carrier in said passage having a portion adapted for axial and rotational movement in said passage, wheel truing mechanism in said carrier, driving means for said mechanism, a standard fixed on said frame having a separable abutment member, spring means between said abutment member and said carrier, and screw thread adjusting means for moving the carrier with respect to the standard.

3. In a grinding apparatus, in combination, a frame, a grinding wheel support on said frame having a passage extending transversely of the grinding wheel axis, a carrier in said passage having a portion adapted for sliding movement in both axial and rotational directions in said wheel support, wheel truing mechanism operably mounted in said carrier, driving means for said mechanism, a motor for operating said driving means, a standard fixed on said frame, and adjusting means for axially feeding the carrier with respect to the standard.

4. In a grinding apparatus, in combination, a frame, a grinding wheel support on said frame having a passage extending transversely of the grinding wheel axis, a carrier adjustably mounted in said passage for axial movement therein, wheel

truing mechanism operable in said carrier, driving means for said mechanism, a standard fixed on said frame, said standard having a foot portion past which the carrier can be moved from said passage and having an abutment portion detachably connected to the foot portion and normally extending across one end of said carrier, spring means between said carrier and said abutment portion, and means for moving the carrier with respect to said abutment portion.

5. In a grinding apparatus, in combination, a frame, a grinding wheel support on said frame having a passage extending transversely of the grinding wheel axis, a carrier in said passage having a portion adapted for axial and rotational movement in said passage, wheel truing mechanism in said carrier, driving means for said mechanism, a standard on said frame, said standard having a foot portion past which the carrier can be moved from said passage and having an abutment portion detachably connected to the foot portion and normally extending across one end of said carrier, spring means between said carrier and said abutment portion, a threaded interconnection between said abutment portion and said carrier, and means for operating the threaded interconnection to move the carrier with respect to the standard.

6. In a grinding apparatus, in combination, a grinding wheel support having a passage extending transversely of the grinding wheel axis, a carrier in said passage having a portion adapted for axial movement therein, wheel truing mechanism in said carrier, driving means for said mechanism, a fixed standard, said standard having a foot portion past which the carrier can be moved from said passage and having an abutment portion detachably connected to the foot portion and normally extending across one end of said carrier, spring means between said carrier and said abutment portion, a threaded interconnection between said abutment portion and said carrier, adjusting means for operating said threaded interconnection, said carrier together with said abutment portion being removable as a unit from said support without disturbing the tension of the spring means, when the abutment portion is detached from the foot portion.

7. In a grinding apparatus, in combination, a frame, a grinding wheel support rotatably adjustable on said frame and having a passage extending transversely of the grinding wheel axis, a carrier in said passage having a portion adapted for radial and rotational movement therein, wheel truing mechanism in said carrier, driving means for said mechanism, a standard fixed on said frame, said standard having a foot portion past which the carrier can be moved from said passage and having an abutment portion detachably connected to the foot portion and normally extending across one end of said carrier, spring means between said carrier and said abutment portion, an adjustable interconnection between said abutment portion and said carrier, said carrier together with said abutment portion being removable as a unit without disturbing the tension of the spring means, when the abutment portion is detached from the foot portion, and means for adjusting said adjustable interconnection to feed the carrier bodily towards the grinding wheel axis.

8. In a grinding apparatus, in combination, a frame, a grinding wheel support having a passage extending transversely of the grinding wheel axis, a carrier in said passage having a housing por-

tion rotatably and axially movable in said passage and having an end wall rotatably adjustable with respect to the housing portion, wheel truing mechanism operably mounted in said carrier, driving means for said mechanism, a fixed standard, and adjusting means between said end wall and said standard, said standard having tracks and said end wall having portions cooperating with said tracks to prevent rotational movements of said end wall.

9. In a grinding apparatus, in combination, a frame, a grinding wheel support rotatably adjustable on said frame and having a passage extending transversely of the grinding wheel axis, a carrier in said passage having a cylindrical portion rotatably and axially movable in said support and having an end wall rotatably adjustable with respect to the cylindrical portion, wheel truing mechanism operably mounted in said carrier, driving means for said mechanism, a standard carried by said frame, adjusting means between said end wall and said standard, said standard and end wall having cooperating portions preventing rotational movements of said end wall and supporting the carrier for axial movements in said passage.

10. In a grinding apparatus, in combination, a frame, a grinding wheel support on said frame having a passage extending transversely of the grinding wheel axis, a carrier in said passage having a housing portion one end of which is adapted for axial and rotational movement in said passage, an end wall for said carrier, means for rotatably adjusting the carrier housing portion with respect to the end wall for adjustment of the housing portion in accordance with the helix angle of the thread to be ground, means including a fixed standard for preventing rotational movement of the end wall, said standard having an abutment portion, and means for adjusting the end wall with respect to the abutment portion.

11. In a grinding apparatus, in combination, a frame, a grinding wheel support on said frame having a passage extending transversely of the grinding wheel axis, a carrier in said passage, wheel truing mechanism in said carrier, a motor in said carrier for operating said mechanism, means for axially adjusting the carrier with respect to the grinding wheel support, one end of said carrier having a sliding fit in said passage and the other end having a rolling support on the frame at opposite sides of the carrier axis at locations radially outwardly of the confines of the passage.

12. In a grinding apparatus, in combination, a frame, a grinding wheel support rotatably adjustable on the frame and having a passage extending transversely of the grinding wheel axis, means for rotatably adjusting the grinding wheel support to tilt the grinding wheel axis in accordance with the helix angle of the thread to be ground, a carrier in said passage having a portion slidably carried in said support for rotational movement therein, wheel truing mechanism in said carrier, driving means for said mechanism, a standard fixed on said frame, said standard and carrier having cooperating portions preventing rotation of the carrier with the grinding wheel support when the grinding wheel support is rotatably adjusted, and means providing for rotatable adjustment of carrier about the axis of said passage.

13. In a grinding apparatus, in combination, a frame, a grinding wheel support on said frame,

a carrier on said support, means for adjusting the carrier with respect to the grinding wheel support, wheel truing mechanism in said carrier and including a pair of wheel trimmer holders, a common mount having holder guides slidably supporting said holders for rectilinear movement parallel to the axis of the grinding wheel in opposite directions, a pair of toggle links interconnecting said mount and one of said holders, a second pair of toggle links interconnecting said mount and the other holder, a positive interconnection between the two pairs of toggle links, and means for moving said mount in said carrier in a direction perpendicular to the grinding wheel axis and at the same time moving said toggle links to move the holders on said mount.

14. In a grinding apparatus, in combination, a frame, a grinding wheel support on said frame having a passage extending transversely of the grinding wheel axis, a carrier in said passage, means for adjusting the carrier with respect to the grinding wheel support, wheel truing mechanism in said carrier and including a pair of wheel trimmer holders, a common mount slidably carried for rectilinear movement in said carrier and having holder guides slidably supporting said holders for rectilinear movement thereon substantially parallel to the grinding wheel axis in opposite directions, means for moving said mount bodily in a direction perpendicular to the grinding wheel axis, and a pair of links interconnecting each of said holders to said mount and arranged to move into alignment to cause relative separation of said holders on said mount.

15. In a grinding apparatus having a grinding wheel support, a truing mechanism for the grinding wheel comprising a carrier mounted in said support for movement perpendicular to the grinding wheel axis, a pair of wheel trimmer holders, a mount slidably supporting said holders for rectilinear movement in opposite directions on said mount, means supporting said mount on said carrier for rectilinear movement in a direction perpendicular to the grinding wheel axis, toggle means for operating said mount towards and from the grinding wheel axis and toggle means for operating said holders in opposite directions on said mount.

16. In a grinding apparatus having a grinding wheel support, a carrier in said support, a pair of wheel trimmer holders, a mount slidably supporting said holders for rectilinear movement in the same plane in opposite directions on said mount, means supporting said mount on said carrier for rectilinear sliding movement in a direction perpendicular to the grinding wheel axis, toggle links adapted for operation thru substantially 30 degrees travel to operate said mount, and means operated by said toggle links for operating said holders in opposite directions on said mount.

17. Wheel truing mechanism comprising a carrier, a pair of wheel trimmer holders, a mount slidably supporting said holders for rectilinear movement thereon in opposite directions, guide means for said mount and providing for sliding movement of said mount on said carrier, toggle links for operating said mount on said guide means, a set of toggle links for operating each of said holders on said mount, and means for operating said toggle links.

18. Wheel truing mechanism comprising a carrier, a pair of wheel trimmer holders, a mount slidably supporting said holders for rectilinear movement thereon in opposite directions, guide

means for said mount and providing for sliding movement of said mount on said carrier, toggle links for operating said mount on said guide means, a set of toggle links for operating each of said holders on said mount, and additional means for advancing and retracting said mount to move said holders toward the wheel at the start of a truing operation and retract the holders from the wheel at the end of a truing operation.

19. Wheel truing mechanism comprising a carrier, a pair of wheel trimmer holders, a mount slidably supporting said holders for rectilinear movement thereon in opposite directions generally parallel to the wheel axis, guide means for said mount and providing for sliding movement of said mount on said carrier towards and from the wheel, a toggle linkage for operating said mount on said guide means, means for moving the holders on the mount during movement of the mount, and additional means for advancing and retracting said mount to move said holders towards the wheel and retract the holders from the wheel at the beginning and end of a truing operation.

20. Wheel truing mechanism comprising a carrier, a pair of wheel trimmer holders, a mount slidably supporting said holders for rectilinear movement thereon in opposite directions generally parallel to the wheel axis, guide means for said mount and providing for sliding movement of said mount on said carrier towards and from the wheel, a toggle linkage for operating said mount on said guide means, means for moving the holders on the mount during movement of the mount, and additional means for advancing and retracting said mount to move said holders towards the wheel and retract the holders from the wheel at the beginning and end of a truing operation.

21. Wheel truing mechanism comprising a carrier, a pair of wheel trimmer holders, a mount slidably supporting said holders for rectilinear movement thereon in opposite directions generally parallel to the wheel axis, guide means for said mount and providing for sliding movement of said mount on said carrier towards and from the wheel, a set of toggle links adapted for rotational movement through 30 degrees travel from one limiting position in which the arms are angularly related into another limiting position in which the arms are substantially in alignment, and means for moving the carrier for feeding movement of the holders.

22. Wheel truing mechanism comprising a carrier, a pair of wheel trimmer holders, a mount slidably supporting said holders for rectilinear movement thereon in opposite directions, guide means for said mount and providing for sliding movement of said mount on said carrier, a set of toggle links adapted for rotational movement through a 30 degree angle from one limiting position in which the arms are angularly related into another limiting position in which the arms are substantially in alignment, and additional means for moving said first set of toggle links to advance the mount towards the wheel.

23. Wheel truing mechanism comprising a carrier, a pair of wheel trimmer holders, a mount slidably supporting said holders for rectilinear movement thereon in opposite directions, guide means for said mount and providing for sliding movement of said mount on said carrier, a set of toggle links adapted for rotational movement through a 30 degree angle from one limiting position in which the arms are angularly related into another limiting position in which the arms are substantially in alignment, for moving said mount towards and from the grinding wheel, and pivotally interconnected arms operated by said toggle links for moving the holders towards and from one another.

23. In a grinding apparatus, in combination, a frame, a grinding wheel support on said frame, a carrier on said support, wheel truing mechanism in said carrier and including a pair of wheel trimmer holders, a common mount having holder guides slidably supporting said holders for rectilinear movement substantially parallel to the axis of the grinding wheel in opposite directions,

a lever pivoted on said mount, means connecting said lever to said holders to move the holders on said mount when the lever is turned, and means for simultaneously turning said lever and forcing said lever bodily in a direction towards the grinding wheel to bodily move the mount in the carrier while the holders move on the mount.

KONRAD RAUCH.
